UNITED STATES PATENT OFFICE.

GEORGE PRZYBYLKO AND STANLEY MICHALEK, OF PEQUABUCK, CONNECTICUT.

MECHANICAL DANCING DEVICE.

Application filed March 24, 1927. Serial No. 178,082.

This invention relates to a new and novel device in the nature of a toy embodying figures representing dancing persons, and a means of revolving the said dancing figures so as to impart the usual dancing motion thereto.

The object of the invention is to provide a toy of novel construction and arrangement of parts, hereinafter more fully described, claimed, and illustrated in the accompanying drawing, in which:

Fig. 1 shows a side elevational view of our improved toy.

Fig. 2 shows a vertical sectional view thereof.

Fig. 3 shows a horizontal sectional view taken on the line 3—3 of Fig. 1.

Fig. 4 shows an enlarged detail view of the disc adapted to support and rotate the dancing figures, as embodied in our improved toy.

Fig. 5 shows a sectional view thereof, taken on the line 5—5 of Fig. 4.

As here embodied our improved toy comprises upright members 10, attached at their lower extremities to the corners of the base member 11. The upright members 10, have their upper extremities formed or shaped, as at 12, so as to represent ornamented posts, such as usually provided in connection with railings, generally employed to enclose dancing pavilions, and the like. The floor member 13, is attached, at its corners, to the upright members 10, adjacent to the upper extremities of the said upright members. The railings 14, are extended between the upright members 10, at or near the upper extremities thereof. The vertical members 15, are extended between the railings 14 and the edges 40 of the floor member 13. The above described construction being such as will represent a dance hall or dancing pavilion, such as above referred to.

The electric motor 16 is attached to the base member 11, and is suitably connected to any convenient source of electric power adapted to operate or drive the said electric motor. The latter mentioned elements not being shown in the accompanying drawing. The flexible member 17, a belt, is extended over the pulley 18, attached to the armature shaft of the electric motor 16, and over the pulley 19, attached to the shaft 20. The shaft 20, is rotatably mounted in bearings carried in the supporting member 21, attached to the upright members 10, intermediate

thereof. The bevel pinions 22 and 23, are attached to the shaft 20, and mesh with the bevel gears 24 and 25, respectively, attached to the shafts 26 and 27, respectively. The 60 shafts 26 and 27, are rotatably mounted in the bearings 28 and 29, carried in the supporting members 30 and 31, respectively, attached to the upright members 10, directly below the platform member 13.

The gears 32 and 33 are attached to the shafts 26 and 27, intermediate thereof, between the supporting members 30 and 31. The pinions 34 and 35, are rotatably mounted on the shafts 36 and 37, respectively, carried 70 in the supporting member 30. The pinions 34 and 35, mesh with the gears 32 and 33, respectively, and with similar gears 38 and 39, respectively. The gears 38 and 39 are attached to the shafts 40 and 41, respectively, 75 rotatably mounted in bearings carried by the supporting members 30 and 31.

The above mentioned shafts 26, 27, 40 and 41, are also rotatably mounted in the bearings 42, carried in the floor member 13. The 80 disc members 43, are provided with centrally located lugs 44, adapted to receive the pins 45, as a means of pivotally attaching the disc members 43, to the upper extremities of the shafts 26, 27, 40 and 41. The disc 85 members 43, are positioned in circular recesses formed in the upper surface of the floor member 13, said recesses being formed so as to provide a low portion 46, and a comparatively higher portion 47, which will 90 cause the said disc members 43 to rise and fall somewhat when rotated by the electric motor 16. The upper disc members 48, are provided with axial extended elements 49, adapted to receive the pins 50, as a means of 95 rotatably mounting the upper disc members 48 or the said disc members 43. The extended members 51, preferably of spring steel, are attached, at one extremity, as at 52, to the floor member 13, adjacent to the periphery of the upper disc members 48, so as to 100 permit the free extremities of the extended members 51, to extend or project over the periphery of the said upper disc members. The expansion springs 53, are attached at 105 one extremity, as at 54, at or near the periphery of the upper discs 48. The expansion springs 53, are attached at their other extremities, as at 55, to the disc members 43. The above described construction being such 110 as will permit the upper disc members 48 to be driven or rotated by the disc members

43, due to gravity, or the weight of the said upper disc members, and which will cause the free extremity of the extended member 51, to engage the screws 54, so as to momentarily stop the said upper disc members 48. The continued, uninterrupted movement or rotation of the disc members 43, will cause the extended members 51 to disengage the screws 54, so as to permit the expansion 10 springs 53, to impart momentarily, accelerated motion to the said upper disc members 48.

The figures 56, representing preferably a dancing couple, namely a man and a woman, 15 are attached or affixed to the upper disc members 48, the above described construction being such as will permit the electric motor 16 to rotate the figures 56, by imparting the motion as hereinbefore set forth, so as to represent or depict dancing couples so as to provide an amusing toy.

It will be understood that the above mentioned shaft 20, may be provided with an extremity 57, adapted to receive a crank, 25 lever, or the like, not shown in the accompanying drawing, as a means of permitting our improved toy to be manually operated.

Having thus described our invention, what we claim as new and desired to protect by 30 Letters Patent of the United States is as follows:—

1. In a toy of the class described, a substantially horizontal platform provided with a circular recess having an inclined 35 bottom surface, an inclined disc rotatively mounted in said recess, an upper disc mounted on said first mentioned disc adapted to be rotated by engagement therewith and figures representing dancers mounted on 40 said upper disc adapted to rotate therewith and to rise and fall periodically as said discs rotate in an inclined plane.

2. In a toy of the class described, a substantially horizontal platform provided with spaced recesses having inclined bottom surfaces, lower discs disposed in said recesses and rotatively guided in an inclined plane by the inclined surfaces of said recesses, upper discs mounted on said lower discs in superimposed relation, shafts disposed through apertures in said platform and pivotally attached at its upper end to said lower disc, driving mechanism operatively mounted below said platform for rotating said discs, and figures representing 50 dancers mounted on said upper discs adapted to rotate therewith on inclined planes for producing combined dancing like rotative and vertical movement.

60 3. A toy of the class described comprising a substantially horizontal platform provided with spaced recesses having inclined

bottom surfaces, lower discs disposed in said recesses and rotatively guided in inclined planes by the inclined surfaces of 65 said recesses, upper discs disposed in superimposed relation on said lower discs and having arcuate slots, a pin mounted in each of said lower discs and disposed in the arcuate slots in said upper discs, abutments 70 mounted on said upper discs in close proximity to said arcuate slots, resilient stops mounted on said platform in the path of said abutments adapted to engage said abutments periodically during rotation of said 75 discs for momentarily positively arresting rotation of said upper discs, and springs attached at one extremity to the pins of said lower discs and at the other extremity to the abutments of said upper discs adapted 80 to rotate said upper discs against the action of said resilient stops after said lower disc has rotated a predetermined amount relative to said upper discs.

4. A toy of the class described, comprising 85 a platform, a lower disc rotatively mounted on said platform, an upper disc having an arcuate slot therein mounted on said lower disc in superimposed relation, a pin mounted on said lower disc and disposed in said 90 arcuate slot, an abutment on said upper disc, figures representing dancers mounted on said upper disc adapted to rotate therewith, a resilient stop mounted on said platform and disposed in the path of said abutment 95 adapted to periodically engage the latter for momentarily positively arresting rotation of said upper disc for producing a dancing like hesitation in the rotation of said figures, and a spring attached at one extremity to 100 the pin of said lower disc and at the other extremity to the abutment of said upper disc adapted to rotate said upper disc at an accelerated speed after said lower disc has 105 rotated a predetermined distance relative to said lower disc.

5. In a toy of the class described, a platform having an inclined recess therein, a disc rotatively mounted in said recess adapted to be rotated in an inclined plane, a second disc mounted on said first mentioned disc adapted to rotate in an inclined plane, figures on said second disc, and means for momentarily positively interrupting the rotation of said second disc for effecting a hesitation in the movement of said figures, said figures being rotated in unison with said upper disc on the inclined plane thereof for imparting to said figures a combined rotative and upward and downward movement.

In testimony whereof we have affixed our signatures.

GEORGE PRZYBYLKO.
STANLEY MICHALEK.
